UNITED STATES PATENT OFFICE.

MARTIN LARSON, OF LA GRANGE, ILLINOIS.

LAST-FORMING MACHINE.

Application filed February 19, 1926. Serial No. 89,258.

The invention relates to last forming machines and has for its prime object the provision of a construction whereby a pattern composed of material of a fragile character such as plaster of Paris may be utilized to provide a means from which to fashion a last of some more substantial and durable material such as wood.

It is therefore an object of the invention to provide an improved construction including a pattern wheel and cutter, the former of which is so mounted and actuated as to engage the temporary plaster pattern and guides the cutter with such light or balanced pressure that a replica of the pattern may be shaped or fashioned from a block without subjecting the plaster pattern to the possibility of injury or breakage, due to either the weight of the mechanism to which the pattern wheel and cutter are attached or the resistance offered to this mechanism during the cutting operation.

It is a further object of the invention to employ improved devices for holding the pattern relatively to certain elements of the machine, which devices will grasp the pattern and also the reinforcing member of a pattern of a new and improved construction as fully described and claimed in my U. S. Patent No. 1,647,639 dated Nov. 1, 1927.

In addition to the above, it is a further object of the invention to employ holding devices for grasping the pattern and the block from which the last is to be fashioned, which devices are movable relatively to each other to adjust said devices to accommodate patterns and blocks of different lengths and to associate with said devices means for holding them in their adjusted relation.

It is also an object to provide a machine of the above character with improved means which may grasp the heel of the pattern and the toe of the last fashioned after the pattern so as to cause the simultaneous rotation of both the pattern and the block.

It is also another feature of the invention to provide means for rotating and simultaneously moving both the pattern and the block lengthwise relatively to the pattern and cutting wheel and to construct said means so that said means and said elements by which the pattern and block are carried may be rapidly restored to their initial or starting position.

The invention will be explained in conjunction with the accompanying drawings

which illustrate a machine constructed according to one embodiment of the invention, it being obvious that changes and modifications may be resorted to without departing from the spirit of the invention as embodied in the appended claims forming a part hereof.

In the drawings,

Fig. 1 is a front elevation view of a machine embodying the invention.

Fig. 2 is an end view of the device shown in Fig. 1 showing certain elements in section.

Fig. 3 is an elevation of a fragment of the pattern and cutting wheel frame of the machine shown in Figs. 1 and 2.

Figs. 4 and 5 are details of the means for clamping the pattern and block to the machine.

Fig. 6 is a sectional view of a portion of a standard provided with means which co-operates with a member for moving the pattern and block relatively to the pattern and cutting wheels, and illustrates a means whereby said member, pattern and block may be rapidly moved to their initial or starting position after the formation of a last.

The embodiment of the invention as illustrated in the drawings contemplates the use of a main frame 10, upon which is mounted an auxiliary frame 11, which carries pattern and block supports generally designated 12, a pattern and cutter wheel frame 13, and a motor 14 for driving the cutting wheel. The auxiliary frame 11 includes a pair of parallel longitudinally arranged supporting bars 15 and 16, which are held stationary relatively to the main frame 10 by means of the vertical supports 17 and 18.

The pattern and block supports generally designated 12 include a plurality of relatively movable separated members 19, 20 and 21, which are held in proper spaced relation from each other by means of the pattern 22 and the block 23 from which latter the last is to be fashioned, and are held in proper associated relation by means of the rods 24 and 25. One end of these rods is fixedly mounted in the member 19 and they each extend through the elements 20 and 21, to allow of their adjustment along said rods and with relation to the member 19 to thereby allow the introduction and removal of the pattern and the block between said members 19, 20 and 21. One end of each of said rods 24 and 25 is provided with threads 26

and each is provided with a nut such as 27 to hold the elements 19, 20 and 21 in proper relation with the pattern and block interposed therebetween. A means is provided 5 for rotating the pattern 22 and the block 23 and simultaneously moving said pattern, block and structure with which the pattern and block are associated longitudinally of the frame along the rods 15 and 16. This 10 means includes the screw threaded member 28, having the hand wheel 29, the member 28 being rotatably mounted in the support 30 which travels along said rods 15 and 16 upon the rotation of the screw threaded member. The screw threaded member 28 is journaled in the support 18 and is in threaded engagement with the internally threaded members 31 which are hinged to the support 18 and are separably secured to 15 together to releasably engage the screw threaded member 28 to allow the rod 28 and its associated elements to be quickly restored to their initial or starting position upon completion of a last. The separable 20 members 31 are separably secured together by means of the thumb screw and bolt 33. Said threaded member 28 is rotatably mounted in a bearing in the movable support 21 and is provided with a clamping 25 element 32 for clamping one end of the block 23 from which the last is fashioned. The threaded members 31 when engaging the threads of the rod 28 by the rotation of the rod, provide a means for feeding the 30 pattern 22, the block 23 and associated elements relatively to the pattern and cutting wheels and frame 13.

The support 19 is provided with means 34 for engaging the pattern 22, and the support 40 20 is provided with means 35 for engaging both the pattern and the block. The means 45 designated 34 is clearly shown in Fig. 4 and consists of a rotatably mounted bearing portion 36 and the stationary and movable clamping elements 37 and 38, the latter of which is pivoted at 39 to allow it to be moved toward and away from the stationary element to releasably clamp the pattern upon the actuation of the thumb screw 40. 50 The element generally designated 35 for engaging both the pattern and the block from which the last is to be fashioned is also provided with a bearing element 41 which is rotatably arranged in the member 20. 55 The element 35 has one end constructed to provide stationary elements 42 and 43 and movable elements 44 and 45, which are separably held by means of the screw and thumb nut 46. The elements 42 and 44 are 60 employed to engage the sides of the pattern 22 while the elements 43 and 45 are designed to engage a wire or other suitably shaped member 47 which extends from the plaster pattern 22 and in the manner shown in Fig. 65 5, as more fully illustrated and described in

my aforesaid co-pending application. It is manifest that when the thumb screw is actuated the movable elements 44 and 45 will be moved on their pivot 48 to release or engage the pattern and extension or reinforcing wire 47. The opposite clamping end of the member 35 and the element 32 substantially correspond to the structure illustrated in Fig. 4, and will therefore not be explained again in detail. 70

The frame generally designated 13 is mounted upon the shaft 49 located in proximity to the frame generally designated 11 and is pivotally mounted in bearings 50 and 51 carried by the main frame 10. This 80 frame includes a pattern wheel frame 52 which includes the parallel arms 52 and 53 fixed to the shaft and which carry the rod 54 at their upper ends upon which the pattern wheel 55 is rotatably mounted between the collars 55', 56 adjustably fixed to said shaft. The shaft 49 extends a suitable distance beyond the bearing 51 and has the arms 57 and 58 adjustably fixed to the shaft 49, which arms extend upwardly from the shaft and carry a flanged pulley 59 and the cutter 60, which are mounted upon the shaft 61 and are driven by means of a belt 62 extending downwardly to the pulley 63 which is a part of the pulley 64 rotatably mounted upon the shaft 49. A belt 65 extends between the pulley 64 and the motor 14 and thus the cutter wheel 60 is driven. It is of course understood that while the wheel 60 is referred to as a cutter wheel, that it is not limited to the use of a wheel having a saw or other cutting teeth as it has been found that a wheel having its annular face covered by sandpaper or emery cloth will perform to an extent the function of shaping 105 the block according to the pattern. The auxiliary frame 13 is provided with a stop 66 for engaging the main frame whereby the outward movement of said frame and associated elements is limited. 110

The belt 62 and the cutter wheel are rotated in a counter-clock-wise direction, as indicated by the arrow in Fig. 2 and thus this direction of rotation of the belt has a tendency to relieve the plaster casting of the 115 weight of the frame carrying the cutter, as it is manifest that the pulling force applied to the belt upon the pulley 59 in the direction above indicated, will materially relieve the fragile plaster pattern of the weight of the cutter and pattern wheel frame. Since the weight of the pattern and cutter wheel frame only is solely relied upon to maintain these wheels in proper co-operative relation with the pattern and block, the force to 120 which the plaster or fragile casting is subjected during the formation of the last is thereby reduced so that a pattern or casting of a very fragile substance as plaster of Paris may be used. 125

From the foregoing description of the structure it is manifest that as the hand wheel 29 and the threaded member 28, are rotated the pattern 22 and block 23 are rotated and moved simultaneously lengthwise of the main frame 11, and by virtue of the fact that the pattern wheel 55 rests upon the pattern 22 rotation and longitudinal movement of the latter will impart transverse movement to the rotating cutter wheel 60 which, by virtue of its contact with the block 23, will cut out of said block a replica of the pattern 22. It will be noted that the frame 13 depends entirely upon its own weight for maintaining the pattern wheel in contact with the pattern 22 which, as before stated, is formed of a material capable of being molded, as plaster of Paris, which is more or less fragile and therefore, it is an object to construct this frame and associated device to arrange them so that they will not subject the pattern to a weight or force which might break or otherwise injure it.

By referring to Fig. 2 it will be noted that the shaft 49 upon which the pattern and cutting wheel frame are pivotally mounted is located parallel to and in substantial horizontal relation to the supporting bar 16. This relative arrangement of these elements, the direction of rotation of the belt 62 and parts driven thereby and the fact that springs, weights, etc. are dispensed with for holding the cutter wheel in associated relation with the block, produces an arrangement whereby the required contact between the cutter wheel and the block is obtained without subjecting the plaster or fragile pattern to any injurious or crushing strain due to the weight of the frame carrying the pattern and cutter wheel and the resistance offered to the cutting wheel by the block.

The structure above referred to, including the separable internally threaded members 31 provided a means whereby the threaded member 28 may be released to permit said member and its associated mechanism to be bodily moved relatively to the pattern and cutter wheel to restore it to its initial or starting position, and also to cause said mechanism to be fed in the reverse direction so as to accomplish the fashioning of a last.

Having thus described my invention what I claim and desire to secure by Letters Patent is:

1. In a machine of the character described, the combination of a frame including sep-

arated parallel stationary members, members arranged transversely of said first mentioned members providing movable supports, means carried by said movable supports which provide devices for engaging a pattern and a block from which a replica of the pattern may be fashioned, a member providing means also carried by said frame for rotating and simultaneously moving said pattern and block longitudinally of said first mentioned frame, and pattern and cutter wheels respectively co-operating with said pattern and block.

2. In a machine of the character described, the combination of a plurality of members for carrying pattern and block supports, a frame upon which said members are slidably mounted, means for holding said members in associated relation to each other, said means providing means whereby one of said members may be adjusted relatively to the other, pattern and block supports carried by said members, one of said last mentioned supports having rotatable means extending therefrom and having screw threaded connection with said frame whereby said pattern and block may be rotated and simultaneously moved longitudinally by the rotation of said rotatable means.

3. In a machine of the character described, the combination of a plurality of members providing pattern and block supports, a frame upon which said members are slidably mounted, means for holding said members in associated relation to each other, said means providing means whereby one of said members may be adjusted relatively to the other, pattern and block supports carried by said members, one of said last mentioned supports having means extending therefrom whereby said pattern and block may be rotated and providing an element of means for moving said first mentioned members longitudinally of said frame, and means for releasing said last mentioned means to thereby allow said pattern and block supports, together with said means for holding said members in associated relation and with said means whereby said pattern and block may be rotated and moved longitudinally of said frame, all to be moved along said first mentioned frame as a unit independently of the rotation of said last mentioned means.

In testimony whereof I have signed my name to this specification, on this 16th day of February, A. D. 1926.

MARTIN LARSON.
